1

This invention relates generally to electrical translating apparatus and has particular reference to such means and methods including translating apparatus for transferring energy between direct and alternating current circuits.

Interrupter devices, more generally known as vibrators, have been extensively used for converting direct current energy into alternating current energy or into direct current energy of a different voltage. In the usual form of these vibrators a reed contact bearing arm usually makes contact with a substantially fixed side contact member at a frequency depending upon the operation of the reed member. Normally because of the natural resilience of one of these members an oscillatory condition known as vibrator "chatter" occurs which acts to decrease the efficiency of the vibrator. Further, because of the unrestrained impact, the abutting contact members become eroded quickly so that after a relatively short time these contacts must be replaced. It is apparent that as the frequency of the vibrator increases these conditions become more pronounced and create a definite operating problem.

At low and medium vibrator frequencies, attempts have been made to meet this problem by providing "stopped" arm vibrator mechanisms in which a stop is provided for abruptly restraining the amount of swing of a compliant contact member. It has been found, however, that at high vibrator frequencies, for example, of the order of approximately 250 cycles per second, this expedient does not work satisfactorily since there is an abrupt forceful stop instead of the graduated cushioned effect desired.

Further, another problem has been found in the construction of high frequency vibrators because of the fact that the power requirements for high frequency vibrators are different than that for low frequency vibrators. Design expedients used for these low frequency vibrators have been found to be unsuited for high frequency operation. This is so because vibrator armatures used in low frequency devices are often constructed so that if used at high frequency operation, maximum power is not obtainable. Particularly is this true since at high frequencies the armature amplitude may be relatively small. Thus, since the power developed by the armature depends to a large extent on the increase of magnetic flux between the pole piece and the armature as it moves toward the pole it is apparent that if the armature construction does not provide for maximum permanence change, the vibrator must be underpowered.

In the present high frequency vibrator inven-

tion these two problems, above, have been faced, and the difficulties resulting therefrom have been substantially overcome, with means being provided for overcoming the losses in vibrator operation due to the use of: (a) improper damping and (b) improper construction of the reed armature.

To overcome the first problem a damped arm mechanism has been provided wherein a compliant contact bearing member is biased against a second compliant member with a follow, or travel relationship thereto, equal at least to the deflection of the contact arm. The two arms, moreover, are cooperatively maintained together so that they do not separate in operation, and have been so constructed that there is a definite frictional motion established therebetween. Thus, in the present novel damped arm construction, a damper spring mechanism is placed behind the contact bearing spring adjacent its associated fixed contacts so that the adjustable relation between the damper spring and its contact bearing member produces an correlative change in contact spacing between the bearing contact and the fixed contact to compensate for the change in spacing between these contacts due to erosion.

Secondly, in order to provide optimum power change between the armature and its associated arm piece, a novel armature is constructed so as to obtain maximum permanence change therein. After great effort and experimentation it was found that the width of the armature is critical in the high frequency construction thereof, and that if the armature width were made substantially equal to the width of its pole piece, then greater permanence change is obtained in the armature as it approaches its pole piece. Further, it was also found that the length of the armature is of a critical dimension; that a definite armature length proportionally related to the width of its associated pole piece provides a dimensional construction such that the permanence change in the armature could be additively affected and improved as it approached the pole piece giving a maximum power efficiency.

By utilizing these findings the present invention includes an armature and pole piece whereby the above criteria are constructionally achieved so as to obtain maximum permanence change in the armature for giving maximum vibrator power. This armature has been constructed having a portion offset from its connected reed structure with a second portion bent in a plane substantially different from the plane of the connected reed structure. Further, the

armature is built to have the same width as its adjacent pole piece.

Thus, this greatly improved high frequency armature cooperating with the novel damped arm mechanism, priorly stated, provides a high frequency vibrator operating with minimum frictional contact losses and at maximum power level.

It is, therefore, an object of the present invention to provide a vibrator using a novel high permanence change type of armature and damped contact arm mechanism having low frictional loss characteristics whereby high frequency operation of the order of hundreds of cycles per second is achieved at a maximum efficiency.

Still another object of the present invention is to provide a high frequency interrupter mechanism having a damped arm contact mechanism and an armature having the characteristic of high permanence change upon its approach to the pole of said interrupter and whereby maximum magnetic flux linkage is thereby provided in said armature.

Still another object of the present invention is to provide a high frequency vibrator assembly having an operating frequency of the order of $N \times 10^2$ cycles per second where N may be an integer greater than 1.

Yet another object of the present invention is to provide in a high frequency vibrator operating above 200 cycles per second a damped arm mechanism having a plurality of springs, one of which rests upon the other so as to dampen its oscillations so that said high frequency vibrator is operative with a minimum of noise.

Another object of the invention is to provide a high frequency vibrator operating at a frequency of the order of hundreds of cycles per second at maximum power and life.

Another object of the present invention is to provide an armature in a high frequency vibrator having the same width as its pole piece and having an extent constructed to give a high permanence change in said armature upon its approach to said pole piece.

Still another object of the present invention provides in a high frequency vibrator a novel armature mechanism having a U-shaped form and providing optimum flux linkage between said armature and its pole piece upon the approach of said armature thereto.

The invention, in another of its aspects, relates to novel features of the instrumentalities described herein for teaching the principal object of the invention and to the novel principles employed in the instrumentalities whether or not these features and principles may be used in the said object and/or in the said field.

Other objects of the invention and the nature thereof will become apparent from the following description considered in connection with the accompanying figures of the drawing and wherein like reference characters describe elements of similar function therein and wherein the scope of the invention is determined rather from the dependent claims.

Referring now to the figures of the drawing: Figure 1 is a front elevational view of an embodiment of the invention useful in showing the constructional arrangement of the separate units thereof;

Figure 2 is a side elevational view of the vibrator invention shown in Figure 1 adapted to show the novel high frequency armature with its associated damped spring mechanism;

Figure 3 is a side elevational view of the frame

structure used in the embodiment of the invention;

Figure 4 is a profile view of the armature and damped arm mechanism shown in the embodiment of the invention shown in Figure 1; and

Figure 5 is an elevational embodiment of the invention showing the use of a pair of felt protector caps enclosing end portions thereof.

Generally speaking, the present invention comprises a current inverter operating at high frequencies of the order of 200 cycles per second. The vibrator includes a high frequency armature connected to a vibrator reed. The armature is multi-sectioned with one of its sections offset from the axis of the adjoined reed, and has a second section bent in a plane substantially differing from the plane of the offset section. The armature is further dimensionally constructed with an extent and width having a direct correlation to the width of its associated pole piece. By means of this construction the high frequency armature is adapted to develop maximum permanence change as it travels towards its pole piece and thus to develop maximum power characteristics.

In addition to the above high frequency armature construction providing maximum power characteristics; the compliant contact members usually connected to the reed of the vibrator have bias springs slideably and frictionally engaging the undersides thereof to increase the high frequency contact efficiency thereof. Thus, each pair of spring members, i. e., the contact member and its bias spring, is cooperatively maintained together so that they do not separate in action when making contact with associated substantially fixed side contacts. In this manner a combined damping and compensating function is achieved by the bias spring so as to adjustably allow for proper contact make between fixed and compliant contacts while compensating for the erosion of the contact points of the vibrator.

Referring now to the drawing, there is shown in an embodiment of the present invention a high frequency vibrator generally designated by reference numeral 8 for operating at frequencies of the order of 200 cycles per second. Vibrator 8 has a hook shaped ferro-magnetic frame having a pair of apertures 122, 123 (Fig. 3) denoted by reference character 10 and has a narrowed hook portion 11 around which there is provided a wire wound driver coil 12 adapted to be current excited from a suitable supply source.

A stack generally denoted by reference character 13 is secured to the lower extremity of ferro-magnetic frame 10 as by means of a single stack screw 14 and nut 15. The stack comprises a plurality of spacers 16, 16a, 16b, 16c which may be fabricated of an electrically resistive material. Between spacers 16 and 16a and 16b and 16c there are included side contact arms 18 and 19 substantially fixedly maintained therebetween as by means of the tight locking afforded by means of stack screw 14 and nut 15. Clamped between spacers 16a and 16b, at its lower extremity, is a hinge member 20 to which is joined a main reed 21 and an armature 30 which may be integrally formed and connected thereto at its upper end. All of the spacers of the stack are provided with an alignment hole through which the stack screw may extend. Side contacts 18 and 19 carry relatively fixed contacts 24 and 25 respectively at the ends thereof and cooperate with the vibrator contacts of the main reed, as will appear presently.

The structure of the vibratory system will be generally understood from Figures 2, 3 and 4. It will be noted that this system is built around reed 9 having a main body section 21, a narrow neck portion 26 integrally formed therewith and shoulders 29 and 31 connecting the said two portions. The entire reed structure 9 is maintained within stack 12 as by the use of resilient hinge member 20 which may be constructed and fabricated of a tempered steel. Resilient hinge 20 has a top section 33, a step section 34 and a narrowly constructed auxiliary reed member 35 integrally formed therewith so as to have a main body portion 36. Hinge 20, it is to be noted, has for purposes of alignment, a hole 39 cut therethrough and also cut-out U-shaped apertures 49 and 46.

At an end 37 of the auxiliary reed 35 there is mounted a vibrator driver contact 38 which is so constructed that it fits between neck section 26 and shoulder 31 of main reed 29 and has main body 36 of auxiliary reed 35 placed in a flat manner adjacent main body section 21 of reed 9. Vibrator driver contact 38 is adapted to cooperate with a normally closed stationary contact 64 mounted at the end 55 of driver contact assembly 42. Assembly 42 comprises end section 41, extension 142 horizontally extending therefrom, a section 43 integrally formed with and vertically extending from extension 42 and a connected top bent section 44 lying adjacent upper portion 50 of frame 10. Bent portion section 44 is mounted against frame 10 as by means of an unitarily formed abutment 51 spot welded to frame 10 at points 60 and 61. In this manner driver contact 64 is maintained in a yielding yet substantially fixed manner for intimate contact with vibrator driver contact 38.

A second stack 70 is provided so as to clamp in a substantially fixed arrangement compliant vibrator arms 71 and 72, reed 29 interposed therebetween, a portion of hinge 20, and spring biasing members 80 and 81 for frictionally engaging arm 71 and 72. The entire assembly is stack constructed by providing metal plates 82 and 83 at each end of second stack 70 for riveting the entire assembly as by means of rivets 85 and 86. Vibrator contact arms 71 and 72 and contact points 90 and 91 placed at the tip ends thereof are adapted on the operation of reed 29 to make contact with associate side contacts 24 and 25. In order to afford frictional bias for vibrator contact arms 71 and 72 which, as stated, are of resilient construction and in order to provide a predetermined amount of cushioning restraint for contact make and break between these members and side contacts 24 and 21, bias spring members 80 and 81 provide individually truncated sections, such as 92, backing up the said compliant arms 71 and 72 in a frictionally slideable manner at a point on vibrator arms 71 and 72 beneath contacts 90 and 91 thereof. It is to be noted that in mounting biasing or backing members 80 and 81 in stack 70 there are provided spacers 107 and 108 between vibrator arms 71 and 72 and biasing members 80 and 81 in order to increase the frictional effects therebetween with the deflection of the members.

Connected to neck 26 of reed arm 29 is a generally U-shaped armature 30 which may be integrally formed therewith. Armature 30 comprises an armature section 100 offset from the reed substantially in a longitudinal plane thereto, a bent portion 103 vertically extending from said offset section and a third section 113 connected to said second section but extending substantially in a plane at right angles thereto.

As stated, hook 11 depends from frame 10 and penetrates coil 12 substantially in the center thereof. Further, coil 12 may have a pair of fiber washers 114, 115 fitted thereagainst in a substantially horizontal plane. At the end of dependent hook 11 is a magnetic pole piece 105. When coil 12 is energized, or current excited, pole piece 105 is adapted to magnetically attract armature 100 at a predetermined frequency. It is to be noted that hook 11 and pole piece 105 have substantially identical end widths less than the width of associated ferro-magnetic frame 10 and as constructionally shown at point 106 thereof.

Since greater mechanical power is required for vibrators operating at a frequency of the order of 200 cycles per second it was found necessary to construct an armature built so as to supply the necessary additional power. Lower frequency armatures, it was found, could not provide the desired power increase. Since the power requirements depend to a great extent upon the permanence change in the armature it was found that an armature was needed which would give increased permanence change with deflection toward the pole piece.

After considerable experimentation it was found that the increased permanence change could be obtained primarily in two ways. It was discovered that the armature end had a direct correlation to the width of its associated pole piece and that for optimum construction of such an armature the width thereof had to be substantially equal to that of the associated pole. In this respect it was found that when the armature end was wider than the pole piece, added permanence was obtained but the permanence change was reduced. Armature ends less than the width of the pole piece reduced the permanence change.

It was further found that the length of the armature was necessarily critical in attempting to obtain maximum permanence change with deflection of the armature toward the pole. This length was found to be greater than the armature thickness. Thus for the necessary permanence change fulfilling the power requirements at high frequency operation of the vibrator it was necessary to provide added length to the armature. This was done by forming the armature end in (a) a generally U-shaped configuration having portions offset to vertical axis of the reed and (b) having a width substantially the same as its adjacent associated pole piece.

In the operation of the present vibrator the circuit organization is substantially generally known to those skilled in the art, and hence does not require any detailed description here. It is sufficient to state that the several contacts are so adjusted that in normal rest position the driver contacts are closed and the other contacts are open. The relatively fixed interrupter side contacts are connected to two ends of the primary windings of a center tapped step-up transformer with the pulsating output taken off the secondary winding of said transformer. A source of low voltage current is connected to the center tap of the primary winding and the main reed. The driver circuit comprises the driver contact connected in series with the driver coil and the source of current.

Upon closing the circuit of the vibrator, the driver circuit will be energized and driver coil 12 will attract armature 30 as by deflecting main reed 9 so as to break the driver circuit. However, the inertia of the vibratory system will

cause continuation of the displacement of the armature of main reed 9 in the same direction until resilient or compliant arm 72 makes contact with its associated side contact member 24. The force from deflected reed arm 72 will now return the vibratory structure in the opposite direction past the center portion thereof until resilient vibrator arm 71 makes contact with its associated side contact 18. The driver circuit will then again be closed between driver contacts 38 and 64 and will again deflect the main and the auxiliary reeds by means of the energized driver coil.

Since, however, the vibrator reed is operating at high frequencies it is necessary, in order to maintain maximum efficiency for the vibrator, that contact make between the separate contact elements be adjusted so as to substantially prevent abrupt contact therebetween in an essentially cushioned manner. Further, since the greater frequency may accentuate the erosion tendencies between the separate contacts it is necessary to provide means for compensation in the spacing between the contacts due to such erosion.

To effectuate the above cushioning between contacts and to compensate for their erosion tendencies the present vibrator mechanism provides a damped arm biasing construction whereby the contact made between the vibrator contact member and its associated fixed side contact is adjusted to provide cushioned contact engagement. Backing spring members 80, 81 are adapted to underlie resilient arms 71 and 72, and to frictionally engage said arms by means of truncated sections 92 thereof. These damper springs 80, 81 bias the vibrator contactors 71 and 72 in such a way that proper relative motion occurs therebetween at maximum deflection. In addition, the damper spring tends to compensate for the spacing changes due to contact erosion. In this manner a damper arm mechanism is provided for biasing vibrator arms of the vibrator so as to prevent abrupt contact make between each vibrator contact and its associated side contact and to compensate for the erosion effects therebetween. Further, in order to substantially completely insure quiet operation for the vibrator, a pair of felt or absorbing caps 120, 121 surround the ends thereof as shown in Figure 5.

The novel high frequency mechanism including a high frequency armature and damped arm mechanism as described above is intended to be merely illustrative and not exhaustive and since many changes could be made herein without departing from the scope of the invention, it is intended that these changes be included here.

What is claimed is:

1. A vibrator comprising in combination, a vibratory reed having a free end, means for supporting the other end of said reed, a driver coil, a frame for holding said coil having one end connected to and supported by said reed supporting means, said frame further being bent to have a hook-like configuration including a dependent portion, said dependent portion penetrating said coil substantially at the center thereof, said portion having its end constructed as a magnetic pole piece, said pole piece and dependent portion both having equal end widths less than the width of the frame from which said latter depends, said support means for said reed and said frame being positioned substantially below said pole piece, a U-shaped armature connected to said reed and cooperating with said pole piece to activate said

reed upon excitation of said coil, vibrator contact arms separate from said vibratory reed included by second support means held on said reed and adapted to move therewith, each of said arms having a frictional backing continuously slideably engaged therewith, and relatively fixed side contact arms held in said first reed supporting means and adapted to make contact with said reed contacts upon the operation of said reed.

2. A vibrator comprising in combination, a vibratory reed having a free end, means for supporting the other end of said reed, a driver coil, a frame for holding said coil having an end connected to and supported by said reed end supporting means, said frame further bent to have a hook-like configuration including a dependent portion, said dependent portion penetrating said coil substantially at the center thereof and having its end constructed as a magnetic pole piece, said pole piece and dependent portion both having end widths less than the width of the frame from which said latter depends, said support means for said reed and said frame being positioned substantially below said pole piece, a U-shaped armature connected to said reed and cooperating with said pole piece to activate said reed upon excitation of said coil, said reed and said pole piece being axially aligned, vibrator contact arms separate from said vibratory reed included by second support means held on said reed and adapted to move therewith, each of said arms having a frictional backing continuously slideably engaged therewith, and relatively fixed side contact arms held in said first reed supporting means and adapted to make contact with said reed contacts upon the operation of said reed.

3. A vibrator comprising in combination, a vibratory reed having a free end, means for supporting the other end of said reed, a driver coil, a frame having an end connected to and supported by said reed end support means for holding said coil placed adjacent said other end of said reed, said frame further having its other end bent to have a hook-like configuration including a dependent portion extending therefrom, said dependent portion penetrating said coil substantially at the center thereof and having its end constructed as a magnetic pole piece, said pole piece and dependent portion both having end widths less than the width of the frame from which said latter depends, said support means for said reed and said frame being positioned substantially below and opposite said pole piece, a U-shaped armature connected to said reed and cooperating with said pole piece to activate said reed upon excitation of said coil, vibrator contact arms separate from said vibratory reed included by second support means held on said reed and adapted to move therewith, each of said arms having a frictional backing continuously slideably engaged therewith, and relatively fixed side contact arms held in said first reed supporting means and adapted to make contact with said reed contacts upon the operation of said reed.

4. A vibrator comprising in combination a vibratory reed having a free end, means for supporting the other end of said reed, a coil-supporting frame having an end connected to and supported by said reed support means adjacent said supported end of said reed, said frame further having its other end bent to have a hook-like configuration including a dependent portion extending therefrom, said dependent portion penetrating said coil substantially at the center thereof and having its end constructed as a magnetic pole

piece, said pole piece and dependent portion both having an end with less than the width of the frame from which said latter depends, said support means for said reed and said frame being positioned substantially below said pole piece, a U-shaped armature of a predetermined length and having a width equal to that of said pole piece and less than that of said reed connected to said reed and cooperating with said pole piece to activate said reed upon excitation of said coil, vibrator contact arms separate from said vibratory reed and included by second support means held on said reed and adapted to move therewith, each of said arms having a frictional backing continuously slideably engaged therewith at a point therealong, and relatively fixed side contact arms held in said support means and adapted to make contact with said reed contacts upon the operation of said reed.

5. A vibrator comprising in combination, a vibratory reed having a free end, means for supporting the other end of said reed, a coil-supporting frame having an end connected to and supported by said means adjacent the supported end of said reed, said frame further having its other end bent to have a hook-like configuration including a dependent portion extending therefrom, said dependent portion penetrating said coil substantially at the center thereof and having its end constructed as a magnetic pole piece, said pole piece and dependent portion both having an end width less than the width of the frame from which the latter depends, said support means for said reed and said frame being positioned substantially below said pole piece, a U-shaped armature connected to said reed and cooperating with said pole piece to activate said reed upon excitation of said coil, said armature having a determined length and a width equal to that of its associated pole piece whereby maximum permanence change is obtained with deflection of the armature toward the pole, vibrator contact arms separated from said vibratory reed and included by said support means for said reed and adapted to move therewith, each of said arms having a frictional backing continuously slideably engaged therewith, and relatively fixed side contact arms held in said support means and adapted to make contact with said reed contacts upon the operation of said reed.

6. A vibrator comprising in combination, a vibratory reed having a free end, means for supporting another end of said reed, a driver coil, a frame having an end connected to said reed end supporting means for holding said coil, said frame further bent to have a hook-like configuration including a dependent portion, said dependent portion penetrating said coil substantially at the center thereof and having its end constructed as a magnetic pole piece, said pole piece and dependent portion both having end widths less than the width of the frame from which said latter depends, said support means for said reed and said frame being positioned substantially below said pole piece, a U-shaped armature connected to said reed and cooperating with said pole piece to activate said reed upon excitation of said coil, angulated vibrator contact arms having contacts at the tips thereof separate from said vibratory reed included by second support means held on said reed and adapted to move therewith, each of said arms having an angulated frictional backing whose tip underlies said contacts and makes engagement with its associated arm only at a point below

5 said contact thus to be continuously slideably engaged therewith while the bottoms of said backing and arms are substantially separated from each other, and relatively fixed side contact arms held in said first reed supporting means and adapted to make contact with said reed contacts upon the operation of said reed.

7. A vibrator comprising in combination, a vibratory reed having a free end, means for supporting another end of said reed, a driver coil, a frame having an end connected to said reed end supporting means for holding said coil, said frame further bent to have a hook-like configuration including a dependent portion, said dependent portion penetrating said coil substantially at the center thereof and having its end constructed as a magnetic pole piece, said pole piece and dependent portion both having end widths less than the width of the frame from which said latter depends, said support means for said reed and said frame being positioned substantially below said pole piece, a U-shaped armature connected to said reed and cooperating with said pole piece to activate said reed upon excitation of said coil, said armature having a portion horizontally offset to said reed, a second portion substantially perpendicular to said offset portion and an end portion bent back toward said pole piece in a plane perpendicular thereto, vibrator contact arms separate from said vibratory reed included by second support means held on said reed and adapted to move therewith, each of said arms having a frictional backing continuously slideably engaged therewith, and relatively fixed side contact arms held in said first reed supporting means and adapted to make contact with said reed contacts upon the operation of said reed.

8. A vibrator comprising in combination, a vibratory reed having a free end, means for supporting another end of said reed, a driver coil, a frame having an end connected to said reed end supporting means for holding said coil, said frame further bent to have a hook-like configuration including a dependent portion, said dependent portion penetrating said coil substantially at the center thereof and having its end constructed as a magnetic pole piece, said pole piece and dependent portion both having end widths less than the width of the frame from which said latter depends, said support means for said reed and said frame being positioned substantially below said pole piece, a U-shaped armature forming an integral connection with said reed by means of a neck portion having a width less than said reed so as to form a pair of shoulders at said connection, said armature cooperating with said pole piece to activate said reed upon excitation of said coil, vibrator contact arms separate from said vibratory reed included by second support means held on said reed and adapted to move therewith, one of said arms being a driver contact arm lying flat against said reed and having its contact placed above said shoulder of said reed adjacent said neck of said armature, said contact on said arm adapted to meet a fixed contact held on an arm connected to said frame, each of said other arms having a frictional backing continuously slideably engaged therewith, and relatively fixed side contact arms held in said first reed supporting means and adapted to make contact with said reed contacts upon the operation of said reed.

9. A vibrator comprising in combination, a vibratory reed having a free end, means for sup-

porting another end of said reed, a driver coil, a frame having an end connected to said reed end supporting means for holding said coil, said frame further bent to have a hook-like configuration including a dependent portion, said dependent portion penetrating said coil substantially at the center thereof and having its end constructed as a magnetic pole piece, said pole piece and dependent portion both having end widths less than the width of the frame from 10 which said latter depends, said support means for said reed and said frame being positioned substantially below said pole piece, a U-shaped armature connected to said reed and cooperating with said pole piece to activate said reed upon 15 citation of said coil, vibrator contact bearing arms separate from said vibratory reed included by second support means held on said reed and adapted to move therewith, each of said vibrator contact bearing arms having a truncated frictional backing continuously slideably engaged therewith only beneath said contacts, and relatively fixed side contact arms held in said first reed supporting means and adapted to make contact with said reed contacts upon the operation 20 of said reed.
